DISPOSABLE CUP

Stanford C. Stone, South St. Paul, Minn., assignor to Plastics, Inc., St. Paul, Minn., a corporation of Delaware

Filed Apr. 10, 1969, Ser. No. 16,660

Term of patent 14 years

Int. Cl. D7—01

U.S. Cl. D44—9

FIG. 1 is a top plan view of a disposable coffee cup, showing my new design;

FIG. 2 is a front elevational view;

FIG. 3 is a right side elevational view;

FIG. 4 is a sectional view on the line 4—4 of FIG. 1;

FIG. 5 is an enlarged scale fragmentary plan view of the handle portion.

I claim:

The ornamental design for a disposable cup, as shown.
